REFRIGERATOR LATCH

Edwin W. North and William O. Burke, Rockford, Ill., assignors to National Lock Co., Rockford, Ill., a corporation of Delaware

Application May 5, 1939, Serial No. 271,852

3 Claims. (Cl. 292—166)

This invention relates to latches, particularly of the automatic or slam-shut variety, a particular object being the provision of improved intermediate lever means in a lock of this type, which means will provide an impositive operating connection between a handle and a bolt so that the handle will not move when the bolt is snapped home responsive to the slamming of the door.

Other objects, advantages and economies peculiar to the invention relate to details of construction as well as the mode of operation of the illustrative embodiment particularly described hereinafter in view of the annexed drawing, in which:

Fig. 1 is a fragmentary horizontal section through the juncture of a door and jamb;

Fig. 2 is a fragmentary vertical section through the door showing the latch and handle, as seen in the direction of line 2—2 of Fig. 1;

Fig. 3 is a transverse vertical section through the latch bolt structure looking in the direction of line 3—3 of Fig. 1;

Fig. 4 is a longitudinal vertical section along line 4—4 of Fig. 1; and

Fig. 5 is a perspective view of the latch including the operating plunger with the top of the mounting bracket removed.

As viewed in Figs. 2 and 4, the preferred form of the latch includes a stirrup or U-shaped mounting bracket 10 formed by bending a metal plate back upon itself to provide an intermediate wall portion or bight 11 flanked by adjoining opposite wall portions 12. These walls 12 are of the peculiar shape seen in plan in Fig. 1, and at one side of the bracket free edge portions are struck up to provide mounting ears 13 (Figs. 3, 4 and 5), while smaller attaching flanges 14 are struck up from another edge portion of the bracket disposed nearly at right angles to the edge portion along which the mounting ears 13 are formed (Figs. 4 and 5).

The latch structure includes a reciprocable bolt 15 secured between a pair of elongated metal straps 16 by rivets 17 (Figs. 3, 4, and 5). At their ends opposite from the bolt, the straps are provided with aligned elongated slots 18 through which projects a rigid pin 19 anchored at its opposite ends in the opposite side plates 12 of the bracket.

One vertical face of the bolt bears against the bight portion 11 of the bracket, and an opposite face of the bolt rides against a roller 20 (Figs. 1, 3 and 5) so that the bolt is firmly guided in its reciprocable movement. An edge portion of the bight or intermediate wall section 11 of the

bracket is turned in to provide a spring mounting lug 21 (Figs. 1 and 4) against which one end of a coil spring 22 bears while its opposite end engages a seating boss 23 on the bolt. Thus, the bolt is normally urged outwardly of the bracket.

The latch is mounted on a plate 24 (Figs. 1 and 2) by means such as the rivets 25 passed through the mounting flanges 14. The plate 24 is secured to the door 26 with the latch structure disposed in a suitable recess therein so that the latch bolt 15 moves in a direction which is nearly parallel to the outer surface of the door for engagement with a suitable latch keeper 27 on the jamb 28.

Means for actuating the bolt includes a reciprocable member or plunger 30 which works in a sleeve 31 mounted on the plate 24 and extending through the inner mounting plate 32 of a handle structure 33, there being a collar 34 threaded onto the sleeve to secure the plates 24 and 32 in assembled relation. A handle member 35 rocks on a pintle 36 and is provided with a bearing surface 37 which bears against the outer end of the plunger 30 when the handle is moved outwardly of the door against the tension of its normal spring 38. A suitable face plate or escutcheon plate 39 shields the handle mechanism from view.

The inner end 40 of the plunger 30 is headed for bearing engagement with an intermediate operating lever or element 42. The arrangement and construction of this intermediate lever is of importance, and it is preferably made by bending a piece of metal back upon itself to provide a bight or intermediate wall portion 43 (Fig. 5 particularly) flanked by opposite adjoining wall sections 44 of approximately triangular shape. Near one corner or apex portion of the opposite triangular walls 44 are aligned openings 45 (Fig. 5) through which a pivot pin 46 is extended (Figs. 1 and 2) and anchored in the opposite wall portions of the bracket.

The intermediate operating lever is thus mounted for movement about an axis which is at right angles or normal to the plane of movement of the bolt 15, and which is parallel with the guiding pin 19 for the bolt. The intermediate wall portion 43 of the lever element is curved inwardly (Figs. 2 and 5) to provide a curved gliding surface which is cooperable with the headed end 40 of the plunger 30. The remaining corner or apex portions of the opposite triangular wall portions 44 are curved slightly as at 47 for bearing engagement with a bearing pin 48 rigidly

mounted between the straps 16 of the bolt structure.

In operating the novel latch, the handle 35 is pulled outwardly of the door (Fig. 2) so that the portion 37 thereof bears against the outer end of the plunger 30, thus moving the latter and the headed portion 40 thereof against the curved intermediate wall portion 43 on the intermediate lever 42 to pivot the latter in a clockwise direction as seen in Fig. 1, whereupon the hooked or curved extremities 47 will bear against the pin 48 and withdraw the bolt against the tension of its spring 22. When the handle is released, this latter spring will restore the bolt to latched position.

Frequently, the handle 35 is released when the door is in open position and thereafter the door may be slammed shut; in such a case, the cammed portions of the bolt 15 will engage correspondingly cammed portions of the keeper 27, and the bolt will be moved inwardly against the tension of its spring independently of the remaining operating mechanism, that is to say, the intermediate lever 42 and the rest of the handle structure. The importance of such independent operation is recognized in the art, the principal feature of the invention being the construction of the mechanism by which such operation is accomplished, particularly with respect to the intermediate means 42-43-47.

The objects and advantages of the invention may be realized in other forms of construction, and the specific details recited herein are not to be considered as limitations except as may be provided in the appended claims.

Having thus described our invention, what we claim as new and desire to protect by Letters Patent is:

1. In a latch of the type having a U-shaped body structure and a reciprocable bolt arranged in said body structure for rectilinear movement, said reciprocable bolt provided with bearing means for engagement by an intermediate operating means and a transversely moving operating plunger, intermediate operating means in the form of a member bent back upon itself to provide a bight portion with opposite adjoining wall portions of approximately triangular shape, said bight portion being curved in a direction inwardly along a line extending between the opposite wall portions for gliding engagement with an end of said plunger, said member being mounted for pivotal movement about pin means extended through said opposite wall portions near an apex extremity thereof, said opposite wall portions having apex extremities remote from said pin means and said bight portion which are curved for bearing engagement with said bearing means on the bolt.

2. Impositive actuating means for use with latches of the type including a housing, a reciprocable bolt arranged for sliding movement in the housing, and a plunger which reciprocates at an angle to the movement of the bolt, said actuating means including a member bent back upon itself and formed to provide opposite plates of approximately triangular shape and connected by an intermediate wall portion which extends from the region of one apex portion of the plates in a direction toward another apex portion and which is curved inwardly of said plates to provide a gliding surface extending toward said plates and adapted for bearing engagement with an end of said plunger, said actuating member being adapted to be mounted for pivotal movement about a pintle extending through said plates in the region near another apex portion thereof, corresponding edge portions of said plates near the remaining apex portion thereof being curved for bearing engagement with bearing means on said bolt.

3. In a latch including a body, a reciprocable bolt structure arranged in the body for rectilinear movement and an operating plunger adapted to move in a direction transversely of the bolt structure to effect movement of the latter through the agency of an impositive connecting means, the combination with said bolt structure and plunger of impositive lever means in the form of a member having opposite faces of approximately triangular shape, said faces being joined by an integral web portion, a bearing pin fixed to said bolt structure, a pivot pin extending through both faces of said lever member near one corner region thereof, said pin extending in approximate parallelism with said bearing pin on the bolt structure and providing a pivotal axis for said lever means, said web being disposed adjacent another corner of said triangular faces, said faces having a curved end portion remote from said pivot pin and said web and projecting to bear in camming engagement with said bearing pin on the bolt structure when the impositive lever means is pivoted in a certain direction, said impositive lever means being mounted with said web portion disposed approximately opposite the end of said plunger and normally in a plane which is not normal to the axis of the plunger, movement of said plunger to project said end against said web effecting movement of the impositive lever means in said certain direction to displace the bolt structure in one direction, said bolt structure being urged into a normal position in an opposite direction by spring means, and means for moving said plunger for the purpose aforesaid.
